UNITED STATES PATENT OFFICE.

WILLIAM F. BAILEY, OF CANTON, OHIO, ASSIGNOR TO THE HOOVER COMPANY, A CORPORATION OF OHIO.

DIE-CASTING MACHINE.

Application filed October 16, 1924. Serial No. 743,971.

An object of my invention is to provide a construction for a die casting machine wherein the furnace or crucible is readily removable for the purpose of renewal or repair and wherein the furnace or crucible may be removed without dismantling the machine.

Other and further objects and advantages of my invention will be described in the specification and defined in the claims appended hereto.

In die casting machines, as previously constructed, it has been necessary to partially tear down the machine and to remove the gooseneck in order that the furnace or crucible may be removed for repair or renewal.

According to this invention a die casting machine is so constructed that parts thereof which may interfere with removal of the furnace or crucible are pivotally mounted so that they may be swung out of the way when it is desirable to remove the furnace or crucible or alternatively and more particularly in connection with the larger size units the construction is such that by the removal of certain furnace supports the furnace may be lowered by an elevator truck and bodily removed.

For a complete description of my invention reference is made to the specification, in connection with the drawings therewith wherein—

Figure 1 is a diagrammatic elevation of a form of pivotally mounted die casting machine.

Fig. 2 is a diagrammatic elevation of a slightly different form of pivotally mounted die casting machine and

Fig. 3 is a diagrammatic elevation of a further form of furnace mounting.

In each of the figures of the drawings like numerals indicate like parts.

In each of the figures of the drawings there is a main support 10, furnace housing 15 and support 11, carrying crucible 12. Supported above crucible 12 is goose neck 13 through the instrumentality of which the molten metal is introduced into the moulds at 14.

In the construction shown in Fig. 1 the entire machine is mounted on heavy beams 15 supported at one end on main support 10 and at the other end on furnace housing and support 11. The die casting machine comprises essentially a ram cylinder 16, ram

rod 17, head 18 and guide and lock cylinder 19. All of these members 16 to 19 are mounted in a rigid frame 20 to the forward part of which is secured the dies 21. Goose neck 13 is pivotally mounted at 22 on a pivoted lever 23 carried by trunnions 24 on beams 15.

In general it is sufficient to mount the goose neck as described since it can pivot sufficiently on its pivoted mounting 22 to allow it to pass dies 21. Should the construction of the machine be such that it does not allow the goose neck to be gotten out of the way then the frame 20 may be mounted in trunnions 25 so that this may also be pivoted.

With the above construction when it is found necessary to remove the crucible, goose neck 13 is swung out of the way through operation of lever 23 and if necessary frame 20 may be swung up and then the crucible 12 may readily be removed without necessitating any dismantling of the unit.

The construction shown in Fig. 2 differs slightly from that shown in Fig. 1 in that the cylinder 16, guide and lock 19, goose neck 13, etc., are mounted directly on beams 15 which are trunnioned at the back end as at 30 to support 10 and are supported and secured at their front ends on and to lugs 31 formed on furnace frame support 11.

With this construction when it is found necessary to remove the crucible it is only necessary to secure a hoist to member 32, provided for this purpose and pivot the structure about its pivot point 30 which will remove the obstructing parts from over the furnace structure and allow access to or the removal of the crucible.

In the construction as shown in Fig. 3 which is adapted for the largest size machines the die casting machine is supported on support member 10 and on the furnace frame 11, the cylinder portion not shown, being also suitably supported. The furnace in this instance is mounted over a pit as 40 and is supported on beams 41. With this construction an elevating truck 42 may be run under the furnace 43 and the furnace lifted slightly for the removal of beams 41 the removal of which allows furnace 43 carrying crucible 12 to be lowered clear of the goose neck 13, after which the truck carrying the furnace may be readily moved to a

convenient place for the removal of the crucible or for repairs.

From the above description it may readily be seen that there has been provided a very simple and convenient means for the removal of the crucible from a die casting machine without necessitating a construction wherein it is necessary to tear down the machine when the crucible needs repair or re-

newal.

I claim—

1. In a die casting machine, a goose neck and its support mounted over a crucible in

combination with means pivotally mounted whereby the goose neck and its support may be removed from over the crucible by pivotal movement of said means. 15

2. In a die casting machine, a frame on which a ram, die and goose neck are carried, a support to which one end of the frame is pivotally mounted and a support for the other end of the frame. 20

Signed at North Canton, in the county of Stark, and State of Ohio, this 15th day of September, A. D., 1924.

WILLIAM F. BAILEY.
